UNITED STATES PATENT OFFICE.

WILLIAM S. CLARK, OF ST. LOUIS, MISSOURI, ASSIGNOR TO MISSOURI GLASS COMPANY, OF ST. LOUIS, MISSOURI, A CORPORATION OF MISSOURI.

DESIGN FOR A GLASS DISH.

SPECIFICATION forming part of Design No. 35,893, dated May 6, 1902.

Application filed April 14, 1902. Serial No. 102,942. Term of patent 7 years.

To all whom it may concern:

Be it known that I, WILLIAM S. CLARK, a citizen of the United States, residing at St. Louis, Missouri, have invented a certain new and original Design for a Glass Dish, of which the following is a full, clear, and exact description, such as will enable others skilled in the art to which it appertains to make and use the same, reference being had to the accompanying drawings, forming part of this specification, in which—

Figure 1 is a bottom plan view of my new design applied to a glass dish, and Fig. 2 is a sectional view.

curved grooves extend outwardly from points adjacent the apices of the star, these grooves forming narrow panels whose faces are ornamented by circular depressions disposed transversely, the ends of such panels having palamated figures. In the narrow panel thus provided by these grooves are triangular raised portions, which are checkered, they being divided by crossing grooves. A small hexagonal figure is formed in this narrow central panel, in the center of which is a small rosette, the marginal face around the rosette being ornamented by pyramidal projections. 35 In the larger panels, which alternate with those just described, there is a cross-groove forming a panel adjacent and between the points of the central star, which panel is ornamented by pyramidal projections. 40 In the hexagonal panel in the center of the dish is a small rosette, around which are arranged pyramidal projections. 45

What I claim is—

The design for a glass dish as herein shown 50 and described.

In testimony whereof I hereunto affix my signature, in the presence of two witnesses, this 10th day of April, 1902.

WILLIAM S. CLARK.
